(57) **CLAIM**

The ornamental design for a cordless drill/screwdriver, as shown and described.

DESCRIPTION

FIG. 1 is a front perspective view of a cordless drill/screwdriver showing my new design;

FIG. 2 is a side view thereof;

FIG. 3 is a top view thereof;

FIG. 4 is the opposite side view of FIG. 2 thereof;

FIG. 5 is a bottom view thereof;

FIG. 6 is a front view thereof; and,

FIG. 7 is a rear view thereof.

The trademark Bosch, appearing in broken lines, is owned by Robert Bosch GmbH; and it, as well as the other broken line indicia seen on the body of the cordless drill/screwdriver, forms no part of the claimed design.
